US0D1010541S

(12) **United States Design Patent** (10) **Patent No.:** **US D1,010,541 S**
(45) **Date of Patent:** **** Jan. 9, 2024**

(54) **CURVED WHEEL LEVELER**

(71) Applicant: **Qingdao Giant Industry & Trading Co., Ltd.**, Shandong (CN)

(72) Inventor: **Hongjian Zhang**, Shandong (CN)

(73) Assignee: **Qingdao Giant Industry & Trading Co., Ltd.**, Qingdao (CN)

(**) Term: **15 Years**

(21) Appl. No.: **29/816,780**

(22) Filed: **Nov. 24, 2021**

(30) **Foreign Application Priority Data**

Nov. 9, 2021 (CN) 202130733483.7

(51) **LOC (14) Cl.** **12-16**

(57) **CLAIM**

The ornamental design for a curved wheel leveler, as shown and described.

DESCRIPTION

FIG. 1 is a rear, right, bottom perspective view of a curved wheel leveler showing my new design;

FIG. 2 is a front, right, top perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines shown on the drawings depict portions of the curved wheel leveler that form no part of the claimed design.

1 Claim, 8 Drawing Sheets
